UNITED STATES PATENT OFFICE.

SAMUEL GREENEBAUM, OF KANSAS CITY, MISSOURI.

BABY-CARRIAGE SCREEN.

1,412,935.

Specification of Letters Patent. Patented Apr. 18, 1922.

Application filed August 25, 1921. Serial No. 495,326.

To all whom it may concern:

Be it known that I, SAMUEL GREENEBAUM, a citizen of the United States, residing at Kansas City, in the county of Jackson and 5 State of Missouri, have invented certain new and useful Improvements in Baby-Carriage Screens; and I do declare the following to be a full, clear, and exact description of the invention, such as will enable others skilled 10 in the art to which it appertains to make and use the same.

My invention relates to improvements in screen attachments for baby carriages and has for its object to provide an extremely 15 simple, yet a highly efficient and durable device of this character which may be readily attached and detached, opened or closed at will, and manipulated in numerous ways without interfering with the swinging of 20 the carriage top from one end of the body toward the other.

With the foregoing in view, the invention resides in the novel subject matter herein-after described and claimed, the descriptive 25 matter being supplemented by the accompanying drawings.

Figure 1 is a side elevation partly broken away and in section, showing the application of my invention to a baby carriage.

30 Figure 2 is a vertical longitudinal sectional view.

Figure 3 is a vertical transverse sectional view as indicated by line 3—3 of Fig. 1.

Figure 4 is an end view looking in the 35 direction indicated by the arrow A of Fig. 2.

Figure 5 is a horizontal sectional view on line 5—5 of Fig. 2.

In the drawings above briefly described, the numeral 1 designates a well known form 40 of baby carriage body having a top 2 which is pivoted at 3 to central brackets 4 so that it may be swung to any number of positions between the ends of the body. The brackets 4 are in the form of open frames and I utilize 45 said brackets in attaching my invention to the carriage.

The numeral 5 designates a base frame 50 which is shaped to correspond to the contour of the upper edge or rim of the body 1 and it will be understood that the shape of said frame may vary in any desired manner, according to the style carriage on which it is to be used. The frame is preferably of channel form as seen clearly in Figs. 2 and 55 3 and said frame is here shown as provided with a lining 6 of felt or any other suitable

material, thus preventing injury to the body. The entire screen is mounted on the base frame 5 and the latter is detachably secured to the body 1 in a novel manner. 60

The numerals 7 designate a pair of spring arms, both of which are preferably formed from a single length of resilient wire as shown, said arms being secured at their upper ends to the frame 5 while their lower 65 ends are adapted for passage through the brackets 4, said ends being shaped to form shoulders 8 which engage the brackets and prevent removal of the arms until they are sprung toward each other. One pair of 70 the arms 7 is located at each side of the frame 5 and since they engage the central brackets 4, the frame 5 is effectively secured at central points to the body 1 and cannot be dislocated thereon by the child within the 75 carriage, the channeled formation of the frame being of course instrumental also in securing it in place.

The screen is of arched formation and preferably consists of relatively fixed and 80 movable sections 9 and 10 respectively, both of segmental form and so associated that the section 10 telescopes with the section 9 when it is opened to any extent. The meeting edges of the sections 9 and 10 are provided with suitable bows 11 which may well have co-acting flanges 12 to form an insect-tight seal when the sections are in closed position as shown in Fig. 2. The bow of the movable section 10 is pivotally mounted 85 in any suitable way as indicated at 13 and any adequate means such as the spring catches 14, may be employed for holding this section in lowered position. Both sections are provided at suitable intervals with 90 arcuate brace bars 15 and the catches 14 may well co-act with a transverse bar 16 secured to certain of the braces 15, said bar 16 being here shown equipped with a handle 17 for raising and lowering movable section 10. 100

By providing a construction such as that shown or the equivalent thereof, it may be seen that the device may be quickly and easily attached or detached, that the movable section 10 may be raised or lowered to any desired extent, that when the screen is completely closed, it is impossible for flies, mosquitoes and the like to annoy the occupant of the carriage, and that regardless of the relative positions 110 of the sections 9 and 10, their peripheral curvature is approximately concentric with and

spaced inwardly from the arc on which the top 2 travels. Thus, the top may be adjusted at will, regardless of the position to which the movable screen section 10 has 5 been moved.

Since excellent results may be obtained from the details disclosed, these details may be followed if desired. It is to be understood, however, that within the scope of 10 the invention as claimed, numerous changes may be resorted to.

I claim:

1. A baby carriage screen comprising a continuous base frame shaped to conform 15 to and adapted to rest on the upper edge of a carriage body, the lower side of said frame being channelled to receive the edge of the body and hold the same in proper shape, means for detachably connecting said frame 20 with the body and an arched screen formed of relatively movable sections mounted on said frame.
2. A baby carriage screen comprising a base frame shaped to conform to and adapt- 25 ed to rest on the upper edge of a carriage

body, an arched screen mounted on said frame and means on said frame to engage the usual supporting brackets of the carriage top and secure said frame detachably in place.

30

3. A baby carriage screen comprising a base frame shaped to conform to and adapted to rest on the upper edge of a carriage body, an arched screen mounted on said frame and a pair of spring arms carried by 35 each side of said frame to engage the supporting brackets of the carriage top and secure said frame detachably in place.

35

4. A baby carriage screen comprising a base frame shaped to conform to and adapt- 40 ed to rest on the upper edge of a carriage body, an arched screen mounted on said frame, and latches depending from opposite sides of said frame to engage the usual supporting brackets of the carriage top and se- 45 cure said frame detachably in place.

In testimony whereof I have hereunto set my hand.

SAMUEL GREENEBAUM.
